WEDGE HEEL SHOE

Frank R. Merritt, Haverhill, Mass., assignor to
United Shoe Machinery Corporation, Flemington, N. J., a corporation of New Jersey

Application September 10, 1940, Serial No. 356,172

4 Claims. (Cl. 12—142)

This invention relates to the so-called "wedge heel" shoes, and for illustrative purposes, is exemplified in a welt shoe having a wedge heel. As generally understood and as used herein, the phrase "wedge heel shoe" is intended to mean a shoe in which the heel extends forwardly to occupy the space usually found beneath the shank of the shoe between the heel breast and the ball line. Since the heel is shaped like a wedge, it is generally referred to as a "wedge heel."

Objects of the present invention are to provide a well-constructed and neat appearing welt shoe embodying a wedge heel and to produce such a shoe by a series of simple operations not beyond the skill of the average operator in a shoe factory. With such objects in mind, the invention provides a welt shoe having a ribbed insole and an upper lasted to the rib. A wedge heel cover is secured at one edge to the upper and insole and at the other edge to a partial insole which underlies the wedge heel and extends from the heel end of the shoe to the ball line, the wedge heel being thus confined between the insole, the heel cover, and the partial insole. A welt is secured to the rib of the insole at the forepart and to the rib of the partial insole at the shank and heel, and, to this welt, the outsole is attached. The invention also provides a simple and efficient method of manufacturing shoes of the character above referred to.

The invention will be better understood when considered with relation to the accompanying drawings in which

Fig. 1 is a perspective view of the insole to be incorporated in a shoe embodying the invention;

Fig. 2 is a perspective view of the shoe after it has been lasted and the wedge heel cover has been stitched on;

Fig. 3 is a perspective view of the partial insole;

Fig. 4 shows the wedge heel;

Fig. 5 shows the heel end of the shoe after the heel cover has been lasted to the false insole and the welt partly sewed on; and

Fig. 6 is a side elevation of the completed shoe.

Referring now to the drawings and more particularly to Fig. 1, the first step in the manufacture of the shoe is the provision of an insole 10 such as that illustrated in Fig. 1. This insole may be of any of the conventional types ordinarily employed in welt shoes, it being provided with an upstanding rib 12 which extends all the way about the periphery of the sole including the heel seat. This insole is tacked to the bottom 55

of a last 14 in the usual manner, and an upper 14, after having been assembled and pulled over, is lasted to the rib 12 according to any of the conventional methods. As illustrated, the lasting margin 18 of the upper is secured in lasted position to the rib 12 of the insole at the sides and around the heel portion by means of staples 16. Lasting of the toe end of the shoe may advantageously be done on a machine of the bed type, the upper being temporarily secured in lasted position by a toe-wire 20 held in place by anchor tacks 22.

The wedge heel cover 24 comprises a piece of upper material of a width somewhat greater than the height of the wedge heel and equal in length to the periphery of the heel. The cover is laid wrong-side-out about the heel end of the shoe with its margin 26 approximately coincident with the edge of the rib 12, and is then secured 20 to the upper and the rib by a seam of stitches 28. The stitching operation may conveniently be performed on a usual welt and turn sewing machine, the welting of course being omitted. As illustrated in Fig. 2, it will be noted that the ends 25 of the cover extend at least to the ball line of the shoe, so that the cover will completely conceal the heel block when it is incorporated in the shoe.

The above operations having been completed, the shoe is prepared to receive a wedge heel 30 such as that illustrated in Fig. 4. In order to insure that the wedge heel will lie firmly on the bottom of the shoe, the inseam 32 formed by the rib, the lasting margin 18 of the upper and the bottom margin 26 of the cover must first be trimmed off so as to form a surface upon which the wedge is to rest. Preferably the trimming will be effected along a line below the staples 26 and above the stitching 28. For reasons later to be explained, it is desirable that the rear ends of the portion of the rib 12 at the forepart of the shoe which is left untrimmed should be cut off abruptly, and this may be conveniently done when the shank and heel portions of the inseam 32 are trimmed.

The trimming operation having been completed, a thin layer of filling material such as ground cork may be applied to the shank and heel portions of the insole to form a flat surface upon which the wedge 30 is then laid in proper position. It may be noted here that the wedge heel 30 has substantially the same peripheral contour as the heel end of the insole and is approximately the same size as that portion of the insole although it may be made slightly larger.

The wedge heel 30 having been positioned and secured to the shoe, for example, by cement, the shoe is ready to receive a partial insole 34. This partial insole is substantially identical with the heel and shank portions of the insole 10, it being cut off approximately at the ball line so that its forward edge is substantially flush with the forward edge 36 of the wedge heel. The forward edge 38 of the partial insole may advantageously be beveled as at 39 so that it will join the insole 10 smoothly without making an irregularity in the shoe bottom, and so that the ends of the rib 40 of the partial insole will abut the rear ends of the rib 12 at the ball line, as shown in Fig. 5. The partial insole is incorporated in the shoe by placing it on the under side of the wedge, that is, the top side of the wedge when the shoe is upside down, as in Fig. 2, and securing it to the wedge either by tacks or cement. Care should be taken that the peripheral contours of the partial insole 34 and of the wedge heel 30 correspond as closely as possible, so that the two are substantially coextensive. With the partial insole in this position, the cover 24 is turned upwardly and is secured in lasted position to the rib 40 of the partial insole by any convenient means such as the staples 42. It will be noted that since the forward ends of the rib 40 and the rearward ends of the rib 12 of the insole 10 at the forepart are alined with each other, a continuous rib will be provided which extends about the entire periphery of the shoe, the junction of the rib 40 and of the rib 12 being made smooth by abutting the rib ends as pointed out previously.

When drawn upwardly and lasted to the rib, in the condition illustrated in Fig. 5, the cover 24 is turned right-side-out and thus neatly conceals the entire wedge heel. In addition to its function in concealing the heel, this cover also forms part of a pocket composed of the cover, the heel and shank portion of the insole 10, and the partial insole 34 in which pocket the heel is tightly confined. It is thus made certain that the wedge heel will not slip but will remain firmly anchored in the position in which it was initially placed. The shoe is now ready for weltting and in this operation a welt 44 is secured to the rib 40 of the partial insole at the shank and heel of the shoe and to the rib 12 of the insole 10 at the forepart by stitching 46. The shoe may then be completed in the manner usual in making welt shoes by attaching an outsole 48 to the welt 44. If desired, a thin piece of wear-resistant material 50 may be secured to the heel end of the sole better to protect it against wear.

By thus confining the wedge heel 30 in the pocket, there is produced a neat appearing and well-constructed welted shoe of the wedge heel type and one having a sole which is substantially flat except for the thin heel piece 50. Such a shoe will be found to be durable and superior to types of wedge heel shoes now being made.

Having thus described my invention, what I claim as new and desire to secure by Letters Patent of the United States is:

1. A shoe comprising a full length insole having a rib, an upper lasted to said rib, a shank and heel wedge, a wedge cover having its upper margin stitched to said upper and rib, a partial insole substantially coextensive with and underlying said wedge, said partial insole terminating at the forward extremity of said wedge and having a rib extending from one side of its forward

end around the heel portion to the forward end of the insole at the other side, the lower margin of said cover being stitched to said rib of the partial insole, and an outsole secured to the shoe.

2. A shoe comprising a full length insole having a sewing rib extending entirely around its margin, an upper lasted to said rib, a shank and heel wedge, a wedge cover having its upper margin secured to said upper and said rib by inseam stitches, said cover and the portions of said upper and said rib in the heel and shank of the shoe being trimmed close to the inseam and said wedge being seated upon the edges of said trimmed inseamed materials, a partial insole underlying and substantially coextensive with said wedge and having a marginal sewing rib extending from one side of its forward end around the heel portion to the forward end at its other side, the forward ends of said rib being alined with the rib on said full length insole, a welt extending entirely around the bottom of the shoe, a continuous line of inseam stitches securing the rear portion of said welt together with the lower margin of said cover to the rib of said partial insole and securing the forward portion of said welt together with said upper to the rib of the full length insole, and an outsole stitched to said welt.

3. That improvement in methods of making wedge heel shoes which comprises providing a full length insole having a sewing rib extending about its entire periphery, lasting an upper to said rib, laying a wedge heel cover wrong-side-out upon said upper rearwardly of the ball line and securing the margin of said cover by means of inseam stitches to said upper and rib, trimming the inseamed materials rearwardly of the ball line but leaving the insole rib and upper untrimmed forwardly thereof, laying a wedge heel upon the trimmed inseamed materials and securing said heel in place, securing to said heel a partial insole substantially coextensive with the heel, turning the wedge heel cover right-side-out and securing it in place to cover the edges of the wedge heel and said partial insole, and securing an outsole to the shoe.

4. That improvement in methods of making welted wedge heel shoes which comprises providing a full length insole having a sewing rib extending about its entire periphery, lasting an upper to said rib, laying a wedge heel cover wrong-side-out upon said upper rearwardly of the ball line and securing the margin of said cover by means of inseam stitches to said upper and rib, making cuts extending inwardly from the edge of said rib approximately at the ball line at opposite sides of the shoe bottom, trimming the inseamed materials rearwardly of said cuts but leaving the insole rib and upper untrimmed forwardly of said cuts, laying a wedge heel upon the trimmed inseamed materials and securing said heel in place, providing a partial insole substantially coextensive with said heel and having a sewing rib extending about the rear and sides of its periphery, securing said partial insole to said heel with the forward extremities of said rib abutting the cut rear ends of the rib of said full length insole, turning said wedge heel cover right-side-out and securing it, together with a welt, to the rib of the partial insole at the shank and heel portion of the shoe and securing said welt to the rib of the full length insole at the forepart of the shoe, and attaching an outsole to said welt.

FRANK R. MERRITT.
